UNITED STATES PATENT OFFICE.

LOUIS BALOG, OF NEW YORK, N. Y.

PROPELLER.

No. 925,265.

Specification of Letters Patent.

Patented June 15, 1909.

Application filed October 7, 1908. Serial No. 456,559.

To all whom it may concern:

Be it known that I, LOUIS BALOG, of the city, county, and State of New York, have invented a new and useful Improvement in 5 Propellers, of which the following is a full, clear, and exact description.

My invention relates to improvements in marine propellers. These propellers as usually made, employ a plurality of blades 10 which are separated in such a way that a great deal of splashing and loss of power is occasioned by rotating them in the water. I am aware, however, that blades few in 15 number and acting continuously like a screw, have been used, but these have not been arranged to produce the best results.

The object of my invention is to produce a two bladed propeller in which the blades project from a common hub and are opposed 20 though of similar pitch, and arranged so as to act continuously upon the water and with little commotion, in a way to get the best grip or kick on the water. In carrying out this idea, I have each blade extend more 25 than half way around the shaft, and construct them so that each takes and leaves the water readily, while the surfaces are pitched so as to get unanimity of action and the best results. Moreover, the blades are 30 shaped as will be presently described, so that when the propeller is reversed it acts as efficiently as when driven forward.

In carrying out the invention, I provide each blade with channels which are oppositely arranged on the two sides, but which are otherwise similar, and which starting from an exceedingly shallow or plane surface, gradually deepen and contract so that the blade grips the water and creates a current having an inward inclination, so that the whole force of the propeller is utilized 40 against the water and without throwing the water to any noticeable extent from the outer edges of the propeller.

Reference is to be had to the accompanying drawings forming a part of this specification, in which similar reference characters indicate corresponding parts in all the views.

Figure 1 is an end view of the propeller 50 embodying my invention; Fig. 2 is a side elevation of the propeller, and Fig. 3 is a cross section on the line 3—3 of Fig. 1.

The propeller has a hub 10 with a hole 11 therethrough to receive the propeller shaft. 55 Projecting from the hub are two similar but opposed blades 12 and 13 which are of simi-

lar pitch but oppositely disposed, so that one begins action before the other leaves off its work. This will be shown clearly by reference to Figs. 1 and 2. It will be noticed by 60 reference to Fig. 1 that each blade extends considerably more than half way around the shaft, and that when viewed in end elevation, the blades largely overlap as will appear from the dotted lines. The blade 12 65 has the beginning and ending points *a* and *a'*, while the blade 13 has the beginning and ending points *b* and *b'*, these being thinned so as to enter the water readily, and of course if the propeller is reversed, the beginning points are reversed. 70

The two blades 12 and 13 are precisely similar though oppositely disposed, and a description of one answers for the other. On each blade is a channel 14 which extends 75 from the hub to the plane surface 15, and near one blade end this channel is relatively wide and shallow, extending from a plane surface, while at the opposite end of the blade the channel is contracted and it is 80 much deeper. Thus on this same surface of the blade a plane 15 is produced which is in direct contrast to the channel, that is, the wider surface of the plane 15 comes opposite the narrower surface of the channel 14. 85

On the opposite side the blade is provided with the same parts 14 and 15, but they are disposed in the opposite direction, so that the shallow end of the channel on one surface of the blade comes opposite the deep part of 90 the channel on the opposed surface. When the propeller is rotated, it will be seen that the water enters the two channels of the two blades which are acting against the water, and is forced inward and somewhat compressed, while the plane surfaces 15 act with a direct forward kick or push. The result is that but little water is forced outward from the periphery of the blades, but the pressure is inward and backward, and so the propeller 95 acts with very little loss of power. This propeller can be made in any size to suit any size of vessel, and my experiments have shown that with a certain number of revolutions I get greater speed from it than from 100 ordinary propellers which I have tried. 105

I have shown the propeller in the form of a single casting, but obviously the blades might be separately made and attached to the hub without affecting the principle of the invention. 110

Having thus fully described my invention,

I claim as new and desire to secure by Letters Patent:—

1. A propeller comprising a hub and overlapping pitched blades projecting from the hub, the blades being opposed but of similar and constant pitch, with oppositely widened channels on the opposed sides of each blade.

2. A propeller having opposed blades of screw pitch, the pitch of the two blades being similar, and the blades being arranged so as to overlap and so as to extend more than half way around its hub, each of said blades having its surfaces partly plain and partly

channeled, the channels extending the whole length of the blades.

3. A propeller having opposed overlapping blades, each blade having on opposite sides a channel relatively wide and shallow at one end and relatively deep at the other, the channels on the opposed surfaces being oppositely arranged.

LOUIS BALOG.
